UNITED STATES PATENT OFFICE

WILLIAM S. HAMM, OF ELKHART, INDIANA, ASSIGNOR TO THE ADLAKE COMPANY, OF CHICAGO, ILLINOIS, A CORPORATION OF ILLINOIS

CURTAIN CONSTRUCTION

Application filed March 10, 1930. Serial No. 434,511.

This invention has to do with the window curtains which are used in automobiles, and is particularly concerned with the so-called battens which are enclosed in the hems in the lower edges of the curtains for coaction with the vertically extending guide cords arranged at opposite sides of the window openings.

Heretofore, it has been the practice to employ wooden sticks as the battens, and fasten ordinary screw eyes in the ends of the sticks and thread the guide cords through the eyes, but such battens give the lower edges of the curtains a rather bulky appearance, and are not very durable, since the sticks will split easily at the locations of the screw eyes when jerked, and the screw eyes will loosen up and come out.

The primary object of this invention is to provide an improved one-piece metal batten which can be made up inexpensively and is not open to any of the above mentioned objections.

Other objects and advantages of the invention will be apparent to those skilled in the art upon a full understanding of the nature of the improvement.

One form of the invention is presented herein for the purpose of exemplification, but it will of course be appreciated that the invention is susceptible of embodiment in other slightly modified structural forms coming equally within the scope of the appended claim.

In the accompanying drawings:

Fig. 1 is an inside view of an automobile window, showing the improved batten;

Fig. 2 is an enlargement of a portion of Fig. 1, showing in detail the manner in which the batten is associated with the curtain and the guide cords;

Fig. 3 is a side view of one end of the batten; and

Fig. 4 is a top view of one end of the batten.

The improved batten, which is adapted to be enclosed within a hem 10 formed along the lower edge of the curtain, consists of a one-piece metal rod 11 which is flattened out and pierced at its ends 12 and 13 to provide circular eyelets in the same plane for the re-

ception of the guide cords 14 and 15. The eyelets are made sufficiently large to accommodate the cords without being too large to pass through the hem at the time of insertion.

The batten can be manufactured very cheaply; requires no assembling prior to or after insertion in the hem; and is practically indestructible since it will bend considerably before actually breaking and may be easily straightened by hand if bent.

I claim:

In automobile window curtain construction, the combination with a vertically movable soft fabric curtain having a narrow hem at the bottom thereof, and vertically disposed guide cords at the sides of the curtain in the plane of the same, of a substantially round one-piece metal rod supported in the hem of the curtain with the ends of the rod projecting from the ends of the hem into engagement with the cords, said rod ends being flattened and widened out in a horizontal plane to a greater width than the diameter of the rod and being provided with circular round-edged apertures for frictionless sliding coaction with the cords.

In witness whereof I have hereunto subscribed my name.

WILLIAM S. HAMM.
